UNITED STATES PATENT OFFICE.

MACK GREEN, OF MONROE CITY, MISSOURI.

BOOT.

No. 799,000.

Specification of Letters Patent.

Patented Sept. 5, 1905.

Application filed July 12, 1904. Serial No. 216,273.

To all whom it may concern:

Be it known that I, MACK GREEN, a citizen of the United States, residing at Monroe City, in the county of Monroe and State of Missouri, 5 have invented new and useful Improvements in Boots, of which the following is a specification.

This invention relates to boot attachments by means of which a boot may be converted 10 from an ordinary knee-boot into a wading or riding boot.

The objects of the invention are to simplify and improve the construction of such devices.

With the foregoing objects in view the invention resides in the precise combination and arrangement of parts and in the exact details of construction hereinafter described and claimed as a practical embodiment thereof.

In the accompanying drawings, forming 20 part of this specification, Figure 1 is a side elevation of a boot having the improvements of this invention combined therewith. Fig. 2 is a vertical section on the line 2 2 of Fig. 1. Fig. 3 is a front elevation showing the means 25 of drawing together the ends of the split clamping-band. Fig. 4 is a section on the line 4 4 of Fig. 3. Fig. 5 is an inside perspective view showing the ends of the split clamping-band.

30 Like reference-numerals indicate corresponding parts in the different views.

The reference-numeral 1 indicates the top portion of an ordinary boot, and 2 a supplementary boot-top adapted to be used in connection therewith. Surrounding the top portion of the boot 1 is a band 3, which preferably is made of metal and is formed with an annular groove which produces on its outer surface a rib 4. It will be observed from Fig.

40 2 that the upper portion of the boot is bent around the annular band 3 and clamped, stitched, or otherwise suitably secured to itself, the metallic band 3 being therefore held within a suitable annular pocket in the 45 top portion of the boot. The supplementary top 2 of the boot is removably fitted over the top 1 adjacent to the metallic ribbed band 3, as shown clearly in Fig. 2, and said supplementary top 2 is held securely in place upon

50 the top 1 and ribbed band 3 by means of a metallic band 6. The band 6 is formed with an internal annular groove 7, adapted to fit over the rib 4 of the band 3. Furthermore, the grooved band 6 is split, as shown at 8, and

55 a perforated lug or bracket, such as 9, is sol-

dered or otherwise suitably attached to each end of said split ring or band, as shown clearly in Fig. 3. A bolt, such as 10, provided with a nut 11, connects the perforated lugs or brackets 9 and serves as a means for drawing together the ends of the split grooved band 6. One end of the split band or ring 6 is formed with an integral grooved tongue 12. The groove in said tongue 12 forms a continuation of the annular groove in the split band 65 or ring. The grooved tongue 12 is adapted to fit slidably into the grooved portion of the opposite end of the split ring, whereby said tongue serves as a means of holding the two ends of the split ring in proper relation with 70 each other and of guiding said ends together when the nut 11 is turned upon the bolt 10 to contract the split ring 6.

From the foregoing description it will be observed that the annular groove in the split 75 band or ring 6 and the annular rib of the band 3 by interlocking with each other, as shown in Fig. 2, serve as a means for preventing displacement of one ring from the other.

The manner of using the improved boot 80 will be apparent from the drawings. When it is desired to convert the improved boot into an ordinary knee-boot, the nut 11 is loosened and the split ring 6 is removed, after which it is possible to remove the supplementary 85 boot-top 2. When it is desired to reconver the improved boot into a thigh-boot, the supplementary top is replaced and the split ring 6 is again fitted around the boot-top and ribbed band 3 to hold the supplementary top 90 securely in position.

By drawing the ends of the split ring closely together through the medium of the bolt-nut 10 the connection between the supplementary boot-top and the ordinary boot-top is rendered 95 water-tight and secure. It will be observed that the ribbed band 3 serves to prevent the compression of the split ring or band 6 from being disagreeable to the leg of the wearer, the annular rib of the band 3 thus serving not 100 only to prevent displacement of the split grooved ring thereon, but also materially to strengthen the band 3 itself, and thus absolutely prevent uncomfortable compression of the boot-top.

105 The annular pocket at the other portion of the boot by which the band 3 is inclosed prevents said band from becoming rusty through the action of perspiration or dampness.

In its particular combination and arrange- 110

ment of parts and in its details of construction the improved boot of this invention constitutes an improvement over the prior art.

Having thus fully described the invention, 5 what is claimed as new is—

The combination of a boot having an annular pocket at the upper portion thereof, a band within the annular pocket made of sheet metal having a central longitudinal rib, a supplementary boot-top removably fitted over the boot-top and ribbed band, a split clamping- 10 band removably fitted over the supplementary top and ribbed band, said band having a cen-

tral longitudinal groove and a grooved integral tongue on one of its ends adapted to fit 15 slidably in the groove of the other end, a perforated lug on each end of the split band, and a clamping-bolt connecting the two perforated lugs and adapted to draw together the ends of the split band.

In testimony whereof I affix my signature in presence of two witnesses.

MACK GREEN.
